PROTECTIVE DEVICE FOR MOVABLE OBJECTS

Leonard James, Raleigh, N. C.

Application June 9, 1953, Serial No. 360,441

1 Claim. (Cl. 109—29)

This invention relates to new and useful improvements and structural refinements in protective devices, and the principal object of the invention is to provide a device conveniently and effectively employed for protecting safes, cigarette dispensing machines, portable phonographs as well as any other similar types of movable objects from being moved, shifted or otherwise displaced by unauthorized persons.

The above object is achieved by the provision of a device which is adapted to be positioned against the object which is to be protected and which contains diffusible agents such as, for example, tear gas, or the like, and is equipped with means for automatically releasing or discharging such agents when the object to be protected is moved relative to the device.

Some of the advantages of the invention reside in its simplicity of construction and in its efficient and dependable operation, and in its adaptability to economical manufacture, and in its adaptability for use in association with movable objects of various types and sizes.

With the above more important objects and features in view, and such other objects and features as may become apparent as this specification proceeds, the invention consists essentially of the arrangement and construction of parts as illustrated in the accompanying drawings, in which:

Figure 1 is a perspective view of the invention, the same being partially broken away so as to reveal its construction;

Figure 2 is a vertical sectional view, taken substantially on the plane of the line 2—2 of Figure 1; and

Figure 3 is a fragmentary elevational view illustrating the invention in readiness for use.

Like characters of reference are employed to designate like parts in the specification and throughout the several views.

Referring now to the accompanying drawings in detail, the protective device is designated generally by the reference character 10 and embodies in its construction a substantially box-shaped housing 12, having an open top and provided on the bottom thereof with pairs of resilient clips 14 to receive removable containers or cartridges 16.

These cartridges are formed from frangible material and contain a quantity of a diffusing agent, such as tear gas or the like.

A transversely extending rod 20 is also secured to the bottom of the housing 12 by a pair of staples 22, this rod having mounted thereon a swingable, substantially U-shaped actuating member 24 which, in its set

position, is disposed in a pair of notches 26 with which one end of the housing 12 is equipped.

A suitable spring 28 is mounted on the rod 20 and operatively engages the bottom of the housing 12 as well as the actuating member 24, whereby to urge the member 24 to a sprung position as indicated by the arrow 30, in Figure 1, wherein the bight portion 26a of the actuating member 24 impacts the frangible containers 16 as shown by the dotted line 32, so that the containers 10 are broken and the diffusible agent contained therein under pressure is released.

The bottom of the housing 12 is provided with an aperture 34 to receive the upper end portion of a stud 36, the latter having a wing nut 38 thereon which engages the inside of the housing 12.

When the invention is placed in use, the housing 12 is positioned against the underside of the object which is to be protected, such as for example a portable safe 40, and a spacer block 42 is placed on the floor 42 under the lower end of the stud 36. Thereupon, with the actuating member 24 in its set position as shown in Figure 2, the wing nut 38 is adjusted so as to sustain the housing 12 in engagement or abutment with the underside of the object 40, while the bight portion 26a of the member 24 also abuts the underside of the object 40, as shown in Figure 3.

Then, when the object 40 is shifted or moved with respect to the housing 12, the stud 36 will slide off the spacer block 42, the entire housing 12 will fall downwardly and the member 24, no longer supported by the engagement thereof with the object 40, will swing as indicated at 30 and impact the containers 16 to discharge the tear gas therefrom.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claim.

What is claimed as new is as follows:

45 A protective device for movable objects, said device comprising a housing adapted to be positioned in abutment with a movable object to be protected, a frangible container provided in said housing and containing a diffusible agent, and means for rupturing said container and releasing said agent therefrom when the stated object is moved relative to said housing, said means including a spring-pressed actuating member pivotally attached to said housing and swingable from a set position in engagement with the stated object to a released position in engagement with said container, together with collapsible means for sustaining said housing in abutment with the stated object, said means being collapsed when the object is moved relative to the housing.
